UNITED STATES PATENT OFFICE.

WILLIAM H. COX, OF COLLEGEVILLE, PENNSYLVANIA.

MOP.

Application filed June 10, 1920. Serial No. 337,883.

To all whom it may concern:

Be it known that I, WILLIAM H. Cox, a citizen of the United States, residing at Collegeville, in the county of Montgomery and State of Pennsylvania, have invented certain new and useful Improvements in Mops, of which the following is a specification.

One object of my invention is to provide an improved mop of the type including wringing rollers and which can be easily and quickly manipulated by a continuous rotation of a hand crank in the same direction to thoroughly wring the cloth.

Another object is to so construct my improved mop that the cloth can be easily and quickly removed and replaced without the entire removal of any securing screws, springs or other small elements; it merely being necessary to loosen adjusting screws to permit the removal of one of the rollers together with the cloth.

A further object is to so make the mop of my present invention that wear can be brought upon all parts of the cloth and for this reason a cloth used in connection with a mop which is made in accordance with my present invention will last an exceptionally long time and give good service until all parts thereof have been worn by use.

Another object is to make my improved mop of a simple and durable construction which can be easily and quickly manufactured.

These objects, and other advantageous ends which will be described hereinafter, I attain in the following manner, reference being had to the accompanying drawings in which—

Figure 1 is a front elevation of my improved mop; a portion of the handle being broken away and the cloth omitted.

Figure 2 is a side elevation of Figure 1; the lower portion of the main frame being broken away to reveal the mounting of the wringing rollers.

Figure 3 is a view of similar character to Figure 1 drawn on an enlarged scale and showing the adjusting screws having been "backed off" to permit the removal of the upper roller.

Figure 4 is a side elevation of Figure 3 showing in full lines the upper roller having been removed and in dot-and-dash lines said upper roller prior to the removal of the same,

Figure 5 is a top plan view of Figure 3.

Figure 6 is a side elevation of Figure 1 looking in the direction of the hand crank,

Figure 7 is a detail front elevation of a yoked auxiliary frame which forms a part of my invention,

Figure 8 is a side view of Figure 7,

Figure 9 is a top plan view of a slide bolt which I preferably employ for locking the hand crank in position during the use of the mop, and

Figure 10 is a fragmentary section taken on the line 10—10 of Figure 3.

Referring to the drawings, 11 represents a looped main frame which is preferably formed of strip metal which is bent in the shape illustrated in Figures 1 and 3; the same including substantially parallel sides 12 and 13, a base 14 which is substantially at right angles to the sides 12 and 13 and two slanting top portions 15 and 16 which are bent substantially parallel at their ends 16^a to embrace a pole handle 17. The ends 16^a are preferably secured to the pole handle by a rivet or screw 18 which extends through said handle. An operating roller 19 is arranged substantially parallel with and closely adjacent the base 14 and has axle portions 20 and 21 which are journaled in circular holes in the respective side portions 12 and 13 of the main frame 11. The axle portion 20 is continued outwardly beyond the side 12 of the main frame to provide a hand crank 22 by which the roller 19 can be rotated. A yoked auxiliary frame 23 is positioned within the main frame 11 with its top bar 24 extending transversely between the upper portions of the sides 12 and 13.

The leg portions 25 and 26 of the auxiliary frame 23 extend substantially parallel with the inner surfaces of the sides 12 and 13 of the main frame and include notches 27 which curve inwardly and upwardly from the edges 28. These notches during the use of the mop form bearings at their inner and uppermost portions for the axle trunnions 29 of another roller 30 around which the mop cloth 31 extends; said mop cloth being shown in dot-and-dash lines in Figure 6. The mop cloth is normally held between the rollers 19 and 30 by resilient means hereinafter described. The leg portions 25 and 26 of the auxiliary frame 23 have outwardly projecting pins 32 which extend into slots 33 which are formed in both of the sides 12 and 13 of the main

frame; said slots 33 being preferably formed entirely within the width of the sides as clearly shown in Figures 2 and 3. The lower ends of the legs 25 and 26 of the auxiliary frame are bifurcated so that the furcations 34 extend at opposite sides of the axle portions 20 and 21. Thus the auxiliary frame is slidably connected within the main frame and is capable of moving in the direction of the lengths of the sides 12 and 13 of the main frame. The top bar 24 of the auxiliary frame has two small posts 35 secured thereto and which project upwardly into the crotch or V-space 36 provided by the oppositely slanting portions 16 of the main frame. These posts 35 freely pass through holes 37 in the pressure bar 38^a; said pressure bar extending substantially parallel with and above the top bar 24.

Coiled springs 38 are interposed between the pressure bar 38^a and the top bar 24 of the auxiliary frame and surround the posts 35. A transverse bar 39 has its opposite ends secured respectively to the oppositely slanting top portions 16 and this bar 39 has screw threaded holes 40 through which pass pressure adjusting screws 41; said pressure adjusting screw bearing on the top of the pressure bar 38^a and having heads 42 within the space 36; said heads being preferably knurled so that the screws can be easily turned by the fingers. Thus by turning down on the screws 41 the auxiliary frame will be moved toward the base 14 of the main frame through the medium of the springs 38 and the roller 30 will be resiliently pressed against the portion of the mop cloth 31 which extends between it and the roller 19.

The transverse bar 39 is preferably provided with a clip 43 which has ears 44 bent upwardly so as to embrace the lower end of the pole handle 17; said pole handle preferably extending into the crotch space 36. Screws 45 or other suitable securing means extend through the ears 44 and provide additional securing means for the handle 17.

A slide bolt 46 has an elongated slot 47 through which rivets 48 on the slanting portion 15 of the main frame extend. The lower end of the slide bolt 46 is forked as shown at 49 and is adapted to slide into a position to embrace the hand crank 22 at a point remote from the operating roller 19 so as to secure the hand crank against accidental rotation during the use of the mop. The opposite end 50 of the slide bolt is preferably bent at an angle to provide a hand hold to permit the forked end 49 to be withdrawn from embracing position with the hand crank 22 when it is desired to wring the mop cloth 31 by turning the hand crank to rotate the roller 19.

65 The notches 27 extends inwardly and up-

wardly to such extend that when the parts are in their operative position to permit mopping, it is impossible for the roller 30 to accidentally move out of said notches 27. In other words, as shown in Figures 1, 2 and 6, it is impossible for the axle trunnions 29 to move downwardly in the notches 27 sufficiently to be freed of the auxiliary frame. However, by backing off the adjusting screws 41 into the positions shown in Figures 3 and 4, the auxiliary frame can be moved into such position that the roller 30 can be moved out of the notches 27 and the mop cloth can then be slid from the roller 30 for purposes of replacement or repair. To re-insert the mop cloth and roller 30, it is merely necessary after the mop cloth has been passed around the roller 30 to insert the axle trunnions 29 upwardly in the notches 27 and to screw down on the adjusting screws 41. This action will move the roller 30 so as to compress the cloth 31 between the rollers 19 and 30 and any desired degree of resilient pressure can be imposed upon the mop cloth according to the amount the adjusting screws are turned; it being noted that the springs 38 serve as a resilient cushion so that the direct pressure of the adjusting screws is converted into a resilient pressure by the interpositioning of the screws 38. This pressure can be regulated to suit the quality and thickness of the mop cloth and when it is desired to wring the mop cloth the same can be done by rotating the roller 19 through the medium of the hand crank 22 and since the mop cloth 31 is in the form of an endless loop, various parts of the cloth can be brought into mopping position so that the cloth will wear substantially equal at all points.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly come within the scope of the appended claims.

Having thus described my invention, what I claim as new and desire to secure by Letters Patent is:—

1. A mop including a main frame having legs; a roller rotatably mounted in the legs; an auxiliary frame having legs vertically slidably relatively to the main frame and provided with notches extending inwardly and upwardly from one of their sides; a roller having axles taking into the notches; means for normally holding the axles in the notches, and resilient means normally holding the rollers in engagement, substantially as described.

2. A mop including a main frame having

slotted legs; a roller rotatably mounted in the legs; an auxiliary frame having legs provided with pins extending into the slots in the legs of the main frame, the legs having notches extending inwardly and upwardly from one of their sides; a roller having axles taking into the notches; means for normally holding the axles in the notches, and resilient means normally holding the rollers in engagement, substantially as described.

3. A mop including a main frame having legs; a roller rotatably mounted in the legs; an auxiliary frame having legs vertically 15 slideable relatively to the main frame and provided with notches extending inwardly and upwardly from one of their sides; a roller having axles taking into the notches; means for normally holding the axles in the 20 notches, means for releasing the axles from the notches, and resilient means normally holding the rollers in engagement, substantially as described.

4. A mop including a main frame; a roller having axle portions journaled in opposite sides of the frame; an auxiliary frame having legs slidably connected to the sides of said main frame and movable in the direction of their lengths, said legs of 30 the auxiliary frame having inwardly and upwardly extending notches; a second roll-

er having axle portions journaled in said notches; a transverse bar secured to said main frame and having screw threaded holes; a pressure bar interposed between 35 said transverse bar and the top of said auxiliary frame; springs interposed between said pressure bar and said auxiliary frame; screws fitting said screw threaded holes and bearing upon said pressure bar; and means 40 for relatively rotating said rollers; substantially as described.

5. A mop including a main frame; a roller having bearings therein; an auxiliary frame having undercut notches; a roller 45 having bearings in said notches, said main frame having slots; and means on said auxiliary frame slideable within said slots, said auxiliary frame slideable within said slots, said auxiliary frame having a forked part adapted to embrace an axle portion of said first 50 roller, said undercut notches leading to the outer surface of said auxiliary frame at a position remote from said forked part; substantially as described.

In testimony whereof I have signed my 55 name to this specification in the presence of two subscribing witnesses.

WILLIAM H. COX.
